UNITED STATES PATENT OFFICE

112,544

DESIGN FOR A TELEPHONE STAND

Ray M. Wiley, Springfield, Mass.

Application September 26, 1938, Serial No. 80,104

Term of patent 3½ years

To all whom it may concern:

Be it known that I, Ray M. Wiley, a citizen of the United States, residing at Springfield, in the county of Hampden and State of Massachusetts, have invented a new, original, and ornamental Design for a Telephone Stand, of which the following is a specification, reference being had to the accompanying drawing, forming part thereof.

I claim:

The ornamental design for a telephone stand as shown.

RAY M. WILEY.
